UNITED STATES PATENT OFFICE.

JOSEPH A. ANGLADA, OF JENKINTOWN, PENNSYLVANIA, ASSIGNOR, BY MESNE ASSIGNMENTS, TO ARCH CUSHION CORPORATION, A CORPORATION OF NEW YORK.

SHOCK-ABSORBING DEVICE.

Application filed June 6, 1923, Serial No. 643,693. Renewed March 14, 1927.

The present invention relates to means for cushioning and modifying blows and shocks in all kinds of apparatus and machinery which are subject thereto in the ordinary or extraordinary course of operation. While the invention is applicable to a great variety of uses, including, for instance, the cushioning of the recoil of guns, etc., it is particularly useful in absorbing the shocks transmitted to the bodies of automobiles and other vehicles; and, in the following description, the invention is set forth with particular reference to this last named embodiment.

In a pending application of William N. Amory, Serial No. 490,081, filed August 5th, 1921, there is described his discovery that, by using a hollow rubber cushion capable of supporting the weight of a vehicle while quiescent, and forcing into such cushion a small quantity of air, not only can the action of the ordinary springs be supplemented in a manner to prevent the disagreeable long swinging movements which follow from the use of springs alone, but the cushions in question can be used as substitutes for such springs, making it possible to suppress their use altogether.

In that embodiment of the present invention herein described, this principle has been taken advantage of, although it is to be understood that certain features of the invention may be used in combination with resilient elements other than that just mentioned.

The principal object of the present invention is the provision of a form of mounting for a cushioning device of the general character above mentioned which is adapted to be applied to vehicle springs arranged in the manner common in the well known Ford car or wherever the shackle operates in tension, wherein the chassis rests upon the middle of a spring placed over and parallel with the axle, the ends of said spring being attached just over the axle by means of short shackles.

In the case of a spring mounting of this character there is not enough room between the points of attachment of each shackle to insert a cushioning device. On the other hand there is ample vacant space over each end of the spring and under the car body, and one object of the present invention is to provide a form of mounting which, while

making this vacant space available, can be easily attached to the spring and axle by merely substituting it for the usual shackle at each end.

Incidentally, the device in question may be utilized in many other arrangements, and either in connection with springs, or attached to rigid members as a substitute for springs. I do not limit myself to its use in the preferred manner herein shown and described.

In the accompanying drawings, Figure 1 is a side elevation of the cushioning device proper which is preferably used, Figure 2 is a plan view thereof, and Figure 3 is a side elevation of the preferred mounting as applied to one end of a Ford spring and axle.

In Figures 1 and 2, a pneumatic cushion, preferably of flat lenticular form, is shown at 10, with the usual air inlet nipple at 11. This cushion is confined between what I term "compression plates", 12 and 13, which are in direct contact with the two circular faces of the cushion; and outside of the compression plates are the "transmission plates" 14 and 15 which lie flat upon the compression plates. The plates 14 and 15 are preferably narrower in one direction than the other, and the longer dimension in one preferably lies at right angles to that of the other. In Figure 2 the transmission plate 14 is shown in full lines, while the dotted lines indicate the outline and position of the plates 15 on the under side. From this it will be seen that these plates lie substantially at right angles to each other.

At the two ends of the plate 14, bolts 16 and 17 pass downward through the upper transmission plate 14, the upper compression plate 12, and the lower compression plate 13, in that order. The heads 18, at the upper ends of these bolts, and the nuts 19 at their lower ends serve to hold the plates named in the positions shown in Figure 1; that is to say with the plates 12 and 13 held flat against the cushion 10, and with the plate 14 in contact with the upper surface of the plate 12. At the same time, since the bolts 16 and 17 are free to slide in the holes in the various plates, it is clear that the plates 12 and 14 may be freely moved toward the plate 13 to compress the cushion 10.

In the same manner and with the same effect, bolts 20 and 21 pass upward through the lower transmission plate 15, the lower

compression plate 13 and the upper compression plate 12, in the order named. The heads 22 and the nuts 23 on these bolts hold the plates together in the same manner as the heads 18 and 19.

In order to attach the cushioning device to the relatively movable members through which any shock is transmitted, each transmission plate is provided with a pair of ears, 10 those on the upper plate being shown at 24 and those on the lower plate at 25.

In another pending application, I have described this cushioning device in full and have claimed its novel features *per se*. In 15 the present case it has been described as the preferred form of cushioning device to be used with the peculiar mounting which is hereinafter claimed. It is to be understood that my broader claims cover the novel 20 mounting in combination with any suitable cushioning means.

In Figure 3 is shown at 26 one side of the forward axle (for instance) of a Ford car, and at 27 is indicated one end of the usual 25 spring upon the middle of which the chassis rests. A curved suspension bar 28 rises from the axle, and, in the usual construction of the Ford car, the extremity of this bar is connected with the adjacent end of the 30 spring 27, by means of a short shackle whose ends are pivotally attached to the bar 28 and the spring 27.

In order to make it possible to substitute a shock-absorbing cushioning device between 35 the spring and bar in place of the ordinary shackle, the mounting herein claimed is employed.

This mounting consists of two transmitting levers 29 and 30, which are united 40 by a pivotal joint 31 in a manner to permit free relative angular movement. The pivotal joint is preferably arranged so that the levers have two short arms on one side and two longer arms on the opposite side, and 45 one or both of the longer arms is bent in a more or less wide curve, as shown on the lever 29, to accommodate the width of the cushioning device.

As shown in Figure 3, the cushioning device is secured between the opposed longer 50 ends of the levers 29 and 30, the ears 24 and 25 being pivotally connected with said levers. The ends of the shorter arms of the transmission levers are pivotally attached respectively to the ends of the suspension bar 28 and the spring 27, in the same manner as the usual shackle is fastened. It will be seen, that the arrangement above described 55 makes available the space under the chassis and over the end of the spring, and at the

same time, since the longer lever arms are applied to the cushioning device, small movements transmitted through the spring 27 are magnified upon the cushion.

Where the preferred form of cushioning 65 device above described, is employed, the cushion 10 is made available for modifying both the primary shock or blow and the rebound.

When the axle is lifted by a wheel striking an obstruction, the primary upward shock is converted by the pivoted levers into a downward thrust, being transmitted through the plate 15, bolts 20 and plate 12, which last compresses the cushion 12 against 75 the plate 13.

The secondary shock or rebound is caused by the tendency of the upper member (the spring 27) to be thrown first upward and then to return, delivering a downward blow. 80 The first or upward movement of the spring is converted by the pivoted levers 29 and 30 into a downward thrust upon the cushioning device. This is transmitted through the plates 14 and 12 which again press the 85 cushion 10 against the plate 13. The second movement, or downward blow, is again cushioned by the element 10 in the same manner. In practice these movements are surprisingly small, and the result is a complete 90 smoothing out of the minor vibrations while checking the swinging tendency of the spring.

It is obvious that the mounting described is equally available in cases wherein the 95 spring 27 is attached to the lower vehicle member, in which case Figure 3 would merely be inverted and 26 would represent the chassis. Indeed a flexible or shock-absorbing mounting of the character described 100 may be used in a great variety of structures and for all sorts of purposes, either to supplement and modify the action of springs or as a substitute for such.

What is claimed is—

In apparatus for the purposes described, a cushioning device comprising a cushion unconfined at its periphery, compression plates thereon, transmission plates outside of said compression plates and slideable bolts 110 uniting each transmission plate with the opposite compression plate; in combination with a pair of transmission levers united by a pivotal joint and having their ends on one side of said joint pivotally secured to the 115 respective transmission plates of said cushioning device.

In testimony whereof I have hereto set my hand on this second day of June, 1923.

JOS. A. ANGLADA.
